STRADDLE CARRIER WITH DUMPING DEVICE

Franz H. Van Hellen, St. Joseph, Mich., assignor to Clark Equipment Company, a corporation of Michigan

Application November 26, 1954, Serial No. 471,188

3 Claims. (Cl. 214—318)

My present invention is directed to a method of, and means for, handling a load, particularly in connection with a load handling vehicle, such as a straddle carrier.

It is an object of my present invention to provide a novel method of handling a load, such as a box of material, which includes, upending the box of material, after it has been deposited on the ground, for dumping the material from the box.

It is another object of my present invention to provide mechanism for a load handling vehicle, which is capable of upending a load lying on the ground forwardly of the vehicle.

It is still another object of my present invention to provide mechanism, which may be incorporated with a load handling vehicle, such as a straddle carrier, for selectively upending a load after it has been transported to an unloading station and deposited on the ground by the straddle carrier.

To accomplish the above objects, I incorporate novel upending mechanism with a straddle carrier, which mechanism includes power operated arm means pivotally connected at one end to the straddle carrier and carrying at the other end load upending means. Considering specifically, a load such as a box of material, the straddle carrier is employed for engaging the box of material on the ground, transporting the box from one location to another, and depositing the box on the ground. After the box of material has been deposited on the ground, the straddle carrier is backed from over the box and the upending mechanism is employed for raising one end of the box so as to upend the latter for dumping the material from the box. Accordingly, it will be seen that the straddle carrier, and the upending mechanism of my present invention, may be employed cooperatively to carry out the method steps of my invention for handling a load, such as a box of material.

Now in order to acquaint those skilled in the art with the method and means for practicing the principles of my present invention, I shall describe in connection with the accompanying drawings, a preferred embodiment of my invention.

In the drawings:

Figure 1 is a perspective view of a straddle carrier with which the dumping device of my present invention has been embodied for carrying out the method of my present invention;

Figure 2 is a front elevational view of the straddle carrier of Figure 1; and

Figure 3 is a side elevational view of the straddle carrier of Figure 1 with the dumping device being shown in several different operating positions.

My present invention is concerned with a new and novel method of handling a load, such as the open-topped tote box shown at 8 in Figure 1. After the box 8 has

2

been filled with material, the following method steps of my invention may be employed for effecting dumping of the material at a distant unloading station. In accordance with my invention, the box of material is first engaged and raised from the ground. This may be accomplished with a load handling vehicle of the character to be described hereinafter. Then the elevated box of material is transported by the load handling vehicle to the unloading station and deposited on the ground. Finally, the box of material is upended from the position shown in solid lines in Figure 1 to the position shown in dot-dash lines in Figure 3 for dumping the material from the box. To specifically perform upending of the box 8, I have invented mechanism which may be embodied with a load handling vehicle in a manner that I shall describe hereinafter.

One type of load handling vehicle which is adapted for use in practicing the method of my present invention is shown in the drawings at 10. This vehicle is commonly termed a straddle carrier, since it carries a load at its underside and thus straddles the load being carried. The straddle carrier 10 comprises a horizontal, generally rectangular, main frame 12 having vertical fork tube housings 14 at each corner. Fork tubes 16 are journaled in the housings 14 and at their lower ends are secured to forks 18 which support horizontal stub shafts 20 upon which the wheel and tire assemblies 22 are mounted. The four sets of fork tubes 16, forks 18, stub shafts 20, and tire and wheel assemblies 22 are rotatable about the vertical axes of the housings 14 for steering the straddle carrier. The main frame 12 supports an operator's cab 24 and a prime mover (enclosed by the hood 26) that is adapted to drive the rear pair of wheel assemblies 22 through power transmission means including a differential unit 28 and a pair of drive shafts, one of which is indicated at 30 in Figure 1. The drive shafts 30 are connected with the wheel assemblies 22 by means of sprockets and chains enclosed by a pair of chain guards 32.

The above described vehicle is provided at its underside with load engaging and elevating means which is operable to hold a load as the vehicle is driven from one location to another.

Extending downwardly from the main frame 12, at each side, is a pipe or post member 34 which is swingable about an axis extending lengthwise of the vehicle. The posts 34 are restrained from swinging movement lengthwise of the vehicle by means of diagonal braces 36. Each post 34 carries a load hook or engaging plate 38, formed with a laterally inwardly directed foot or ledge 39, which is movable upwardly and downwardly on the post 34 by hydraulic piston and cylinder assembly means (not shown) acting through links 40. The selective movement of the plates 38 toward and away from each other, and up and down, permits loads to be engaged and discharged conveniently, at the will of the operator of the vehicle.

I shall now describe the upending mechanism of my present invention which, when incorporated with a load handling vehicle, is operable to tilt a dump or tote box, such as is shown at 8 in Figure 1, to empty the contents thereof. The upending mechanism is particularly adapted for embodiment with the above described straddle carrier and comprises forwardly extending arm means including a pair of lengthwise extending arm members 44 which are disposed at the sides of the vehicle 10. The rear ends 60 of the arm members 44 are pivotally mounted at 46 about a transverse axis to the main frame 12 of the vehicle adjacent the rear end thereof. The forward ends of the arm members 44 are curved downwardly and at their forward

termini support load upending means in the form of a horizontal, transversely extending, load upending bar or rod 48. Additional rigidity of the arm members 44 is obtained by means of a transverse brace member 49.

To perform its upending functions, the load upending bar 48 is moved upwardly and downwardly at the forward end of the vehicle. Such movement is effected by pivoting the arms 44 about the mountings 46 with power actuated means including a pair of chain assemblies 50. Each chain assembly 50 is secured at its one end to the adjacent arm 44 and at its other end to the main frame 12 of the vehicle. In addition, each chain 50 is trained over a sprocket 52 that is pivotally mounted on the adjacent end of a transversely extending shaft 54. The shaft 54 is carried at the outer ends of the piston rods 56 of a pair of hydraulic piston and cylinder assemblies 58 having cylinders 60 secured to the main vehicle frame 12 inwardly of the sides thereof. The chains 50 and sprockets 52 serve as motion transmitting means between the hydraulic assemblies 58 and the arm members 44. The hydraulic assemblies 58 are operated by a conventional fluid pressure control system for effecting upending of a load.

Upon the admission of fluid under pressure to the lower ends of the hydraulic cylinders 60, the piston rods 56 are distended upwardly, and the chains 50 are caused to travel in a counterclockwise direction over the sprockets 52. This action causes the ends of the chains 50, which are secured to the arms 44, to be drawn upwardly and effects clockwise pivotal movement of the arms 44 about the mountings 46. The load upending bar 48 is elevated as the arms 44 are pivoted clockwise.

To lower the load upending bar 48, fluid is bled from the lower ends of the cylinders 60 while fluid under pressure is simultaneously directed to the upper ends of the cylinders 60. This causes the piston rods 56 to be retracted and the chains 50 to travel in a clockwise direction over the sprockets 52. Thus, the ends of the chains 50 which are secured to the arms 44 are played out and the arms 44 are permitted to pivot counterclockwise about the mountings 46.

One form of dump or tote box 8 which is particularly adapted for use in practicing my present invention comprises, as shown in Figure 1, vertical sides 62 spaced apart by a rear wall 63, and a bottom 64 having straight and inclined portions. Spaced runners 66 are employed to reinforce both the straight and inclined bottom portions 64. Suitably secured to the rear box wall 63 are a pair of rearwardly extending arm members 68 having cut-out portions 70 which serve to receive the load upending bar 48 whereby the tote box 8 may be upended upon suitable actuation of the upending mechanism.

The following is a description of my novel method of handling the box 8 with the above-described straddle carrier and upending mechanism of my present invention. After the box 8 has been filled with material, the straddle carrier 10 is driven over the box 8 so as to dispose the box under the main frame 12 as shown in solid lines in Figure 3. The load engaging plates 38 are then lowered on the posts 34 and the latter are swung laterally inwardly toward each other for disposing the plate feet 39 beneath the box 8. Finally, the load engaging plates 38 are elevated on the posts 34 for raising the box 8 from the ground to the position shown, for example, in dot-dash lines in Figure 2. The box 8 is now in position to be transported by the straddle carrier 10 to an unloading station.

After being transported to the unloading station, the box 8 is deposited by lowering the load engaging plates 38 until the box contacts the ground and by swinging the posts 34 laterally outwardly so as to withdraw the plate feet 39 from beneath the box. Then, to permit upending of the box 8, the straddle carrier 10 is backed away from the box to approximately the position shown in Figure 1.

Upending of the box is carried out by lowering the load upending bar 48 to the position shown in solid lines

in Figure 3 below the cut-out portions 70 of the box. The hydraulic piston and cylinder assemblies 58 are suitably actuated by the operator of the vehicle so as to move the load upending bar 48 progressively upwardly into the cut-out portions 70 shown in dash lines in Figure 3, through the position shown in dash-double-dot lines in Figure 3 and hence to the position shown in dot-dash lines. During this movement of the load upending bar 48, the box 8 is raised at its one end, rocked about the runners 66 from the straight to the inclined portions, and finally is tilted to the vertical position shown in dot-dash lines in Figure 3.

At this point, the material, which has been loaded in the box, will fall from the box under the force of gravity. If the material tends to adhere to the inside of the box, the latter may be jogged or jostled, by suitable actuation of the hydraulic piston and cylinder assemblies 58, while the straddle carrier is slowly backed away from the material being dumped. After the box 8 has been emptied, it is returned to its normal horizontal position shown in Figure 1 by lowering the load upending bar 48 while slowly moving the straddle carrier backwardly. The box 8 is then returned by the straddle carrier to a storage point, or a loading zone where it may again be filled with material that must be transported from one position to another.

From the foregoing description, it will be realized that the straddle carrier, and the upending mechanism of my present invention, may be cooperatively employed to carry out the method steps of my present invention which include upending the box of material, after it has been deposited on the ground, for dumping the material from the box.

Now while I have shown and described what I believe to be preferred method and means for carrying out the principles of my present invention, it will be understood by those skilled in the art that various rearrangements and modifications may be made therein without departing from the spirit and scope of my invention.

I claim:

1. In an industrial material handling vehicle of the type equipped to straddle, elevate, transport, and deposit box-like containers, the combination comprising, a horizontal load upending bar disposed across the forward end of the vehicle, parallel arm members supported on the vehicle and carrying said bar therebetween, selectively operable power actuated means having connection with said arm members for raising and lowering said bar substantially vertically, and engagement means on the container adapted to be coupled with said bar whereby the container may be upended and its contents discharged by upward vertical movement of said bar.

2. In an industrial material handling vehicle of the type having a main frame and equipped to straddle, elevate, transport, and deposit box-like containers which are fitted with engagement means at one end thereof, the combination comprising, a horizontal load upending bar disposed across the front end of the vehicle, parallel arm means connected at one end to said load upending bar and pivoted at their opposite ends to the main frame of the vehicle, and power actuated means carried by the vehicle and having connection with said arm means for effecting pivotal movement of the latter thereby to raise and lower said upending bar as selected, the raising of said bar when the same is connected with the engagement means on the container causing the latter to be upended to discharge its contents.

3. In an industrial material handling vehicle of the class adapted to straddle, elevate, transport, and deposit box-like containers, the combination comprising, a horizontal upending bar disposed across the forward end of the vehicle, parallel arm means supporting said bar at its ends, means pivotally connecting said arm means to the vehicle, hydraulic piston and cylinder means carried by the vehicle, motion transmitting means including sprocket

and chain means interconnecting said arm means and said hydraulic piston and cylinder means, means for selectively operating said hydraulic piston and cylinder means to elevate and depress said bar in response to pivotal movement of said arm means, and load engagement means provided on one end of the container for selective engagement by said bar, the elevation of said bar when engaged with the said load engagement means serving to upend the container and unload the same.
